UNITED STATES PATENT OFFICE

2,513,506

VIEWER AND WATER SPRAYER

Daniel Mendelson, Brooklyn, N.Y.

Application February 10, 1948, Serial No. 7,449

3 Claims. (Cl. 272—27)

1 My invention relates to toys and fun-makers, and more specifically to a type of fun-maker used in perpetrating a practical joke. The device, a false viewer, sprays water.

Heretofore, viewer devices for perpetrating a practical joke have not resembled true viewers enough to deceive a discerning person, the lack of resemblance being mainly due to the omission of a crank and to the general crudeness of the structure. A device to resemble a viewer should be shapely formed, substantial and expensive in appearance and, in addition, be provided with a lens, a picture and a crank-arm.

Therefore, it is an object of my invention to form my device with care, especially noting the little details which permit the deception to be complete.

Another object is to provide a crank for the operation of the device, as cameras and picture devices are always associated, in a person's mind, with cranks.

A further object is to form my device, as completely as possible, of simple and easily and inexpensively obtained standard elements in order to permit their rapid and inexpensive assembling.

Water spraying devices dispensing a large amount of water over a considerable area are not fun-makers but cause ill-feeling and arguments.

Therefore, an object of the invention is to form the dispensing device so that it is held close to the face when operated, resulting in the operator's face only being wetted and no other part of his person. Furthermore, the device is formed so that only a small stream of water is sprayed, preventing the operator from actually becoming annoyed or discomfited.

I accomplish these and other objects by forming my viewing and spraying device of a container having a front, rear and sides and a water containing and evicting means, the means being a collapsible bulb and a pressure arm positioned within the frame and capable of exerting pressure on the bulb, and a handle positioned exterior to the frame at its side and being capable of motivating the arm, the front of the frame having a picture and rear of the frame a lens and a water exhaust hole.

For further comprehension of the invention, and of the objects and advantage thereof, reference will be had to the following description, the accompanying drawings and to the appended claims in which the various novel features of the invention are more particularly set forth.

Fig. 1 is a perspective view of a viewer and

2 sprayer embodying my invention, showing the rear and sides of its container.

Fig. 2 is a perspective view of the same viewer but showing the front and sides of the container.

Fig. 3 is a perspective view, partly broken away, showing a water containing bulb and its compressing means.

Fig. 4 is a sectional view along the line 4—4 of Fig. 1 showing a lens, the water containing bulb and its compressing means, and a handle.

Fig. 5 is a sectional view along the line 5—5 of Fig. 1 showing the side of the elements shown in Fig. 4.

In the drawing and in the specification, in which like numerals indicate similar elements, a viewer and sprayer 10 is shown comprised of a container 11, a compressible bulb 12, and a water evicting means 13.

The container or box 11 is comprised of a body element 14, and two closure caps 15 and 16. The body element 14 is tube like, in shape, and its forward and rear ends are closed and encased by the caps 15 and 16, respectively. The caps are secured about the element 14 by coacting nodes 17 and dents 18 on the caps and element, respectively. The container is assembled by positioning the caps over the body element ends, care being taken that the nodes are positioned in the dents.

The cap 15, is provided with an opening 19 and, at either side thereof, a catch 20, the catches being formed to carry or support, across the opening, a small film or paper 21 containing a picture or scene, in the present case a picture of a dog.

The cap 16 is provided with an opening 22 having a shouldered section 23 and a rim 24. A lens 25, positioned inside the container, is held against the rim by an annular washer 26, which is force fitted against the shouldered section of the opening. The opening 22 and its lens 25, are positioned axially aligned with the opening 19 and its picture 21, so that a person examining the device, holding it to his eye and looking thru the lens, actually views a scene and believes he is operating a viewing device.

The cap 16 is provided, in addition to its opening 22, with a hole 27 carrying a tube 28 which extends inwardly and outwardly of the container. The tube is formed with a closure element 29, across its exterior end, and a flange 30 which rests against the outer face of the cap about the hole. The closure element 29 is punctured by a small exhaust hole 31, suitable for the eviction of a small stream of water. The portion of the tube extending within the container is bushed by a

washer 32 of substantial thickness and formed of rubber or other resilient material. The tube and cap are firmly secured together, the edges of the washer 32 and the face of the flange 30 resting closely against the inside and outside of the cap.

The compressible and collapsible resilient bulb 12, which is formed with a neck portion 33 and a bulb portion 34, is positioned lengthwise within the box, with its neck encircling the bushing or washer 32.

The water evicting means 13 is comprised of a plate 35 and a crank 36. The plate is positioned over and close to the bulb and has a section 37 almost the width of the container resting above the enlarged portion of the bulb and a narrower section 38 resting over the neck and smaller portion of the bulb. In addition, the plate is provided with a tongue 39, bent over to form a bearing for rotatably holding the crank.

The reciprocatable and rotatable crank 36 is shaped with an offset section 40 and terminates at one end in an angled arm 41 and a crank handle 42, the offset section being positioned within the container and the arm and handle outside and at the side of the container. The crank is supported at one end, by a bearing 43 in the side of the container body 14 and between its offset section and its angled arm by a hole 44, which acts as another bearing.

The plate 35 is supported by the crank 36, the tongue 39 of the plate rotatably hooking over and holding the offset section 40 of the crank. The narrow section 38 of the plate resting adjacent the bearings 43 and 44, and the wider section 37 extending forward of the crank. The section 37, being almost the width of the container, retains the plate in proper alignment in the container. When the crank is rotated, given a fraction of a turn, the plate is forced downwardly, the bulb is squeezed and the liquid, or part of it, is forced outwardly through the tube 28 and its exhaust or vent hole 31.

The bulb is filled with water or other liquid by holding the end of the container having the hole 31 into water or other liquid while turning or rotating the crank handle downwardly to compress the bulb and then upwardly permitting the water to flow into and fill the bulb.

A person looking through the lens sees the picture but does not see the plate or bulb which is below the line of vision and so does not realize the true character of the device.

Thus, when he rotates the crank arm believing he is aligning or focusing a new picture, he is surprised to find himself being wetted by his own act.

The device is simply constructed by positioning the picture on the forward cap; adding the lens, tube, bushing and bulb to the rear cap; weaving the crank through the container body to its bearings and hooking the plate onto the crank; and then forming the caps and container body into the completed viewer and water sprayer.

Although I have shown and described only the main form of my viewer and water sprayer many other forms are possible without departing from the spirit and scope of the ideas conveyed in the drawing and specification and so I desire to cover all modifications, forms and embodiments of my invention which may come within the

scope and language of any and all of the claims.

Having thus described my invention, what I claim as new and desire to secure by United States Letters Patent is:

- 5 1. A viewer and fluid dispensing device comprised of a box, a compressible bulb reservoir and a pressure means within the box and near one another for dispensing the bulb's contents, said box bearing in its opposing ends a configuration and an eye piece for examining said configuration and having, to the exterior of one of its sides, a crank handle thus simulating a multiple frame picture viewing device, said handle, in addition, being operably secured to and motivating the pressure means, said bulb having a venting passageway terminating in an opening adjacent the eye piece, whereby when the spectator examining the configuration with his eye to the eye piece operates the crank handle with the intent of changing frames he actually motivates the dispensing device and forces whatever fluid there may be stored in the reservoir into his face.
- 10 2. In a viewer and fluid dispensing device, a box having an eye piece simulating a lens and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably positioned adjacent to and capable of motivating the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 15 3. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 20 4. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 25 5. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 30 6. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 35 7. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 40 8. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 45 9. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 50 10. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
- 55 11. In a viewer and fluid dispensing device, a box having an eye piece and a configuration aligned with said eye piece, an articulatable element simulating a frame changer projecting from the box, and fluid retaining and dispensing means disposed within the box and including a vent opening through a wall of the box in the vicinity of the eye piece, said articulatable element being operably connected to the retaining and dispensing means, whereby when a spectator examining the configuration with his eye to the eye piece operates the articulatable element ostensibly to change picture frames he actually motivates the fluid retaining and dispensing means to discharge the contents thereof through said vent into his face.
